UNITED STATES PATENT OFFICE.

PAUL F. SHIVERS, OF WABASH, INDIANA, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE.

FLUID-FUEL-BURNER CONTROL.

Application filed May 7, 1927. Serial No. 189,479.

The object of my invention is to provide a simple and efficient means for automatically controlling the action of a fluid-fuel burner so that it may be depended upon to permit automatic normal operations of the burner but will prevent delivery of fuel in all cases of accidental failure of ignition or combustion.

The accompanying drawing illustrates my invention diagrammatically.

10 Flow of current from the main power leads 10 and 11 is controlled by a room thermostat T (and associated controls such as a boiler control B, if desired) connected by a wire 12 to leaf 13 of the warp switch W, said leaf 13 being normally held in contact with a terminal 14 by the bimetallic blade 16 of the warp switch, the leaf 13 being insulated from blade 16 and biased away from terminal 14 by spring 17.

20 The heating coil 18, which is associated with blade 16 to cause its warping, has one end electrically connected to blade 16 and its other end is connected by wire 19 with terminal 14.

25 A wire 20 connects heating coil 18 by wire 19 with a terminal 21 projected into one end of a mercury tube 22 which forms the circuit changing element of the combustion control C.

30 The combustion control C is a circuit determining device sensitive to combustion conditions closely adjacent the burner and may conveniently be a well known thermostatic device which, while movable through a wide range serves to change circuits promptly upon rise or fall of temperatures.

35 Paired with terminal 21 is a terminal 23 which is electrically connected to a terminal 24 at the opposite end of tube 22. Terminals 23 and 24 are connected by wire 24' with blade 16 of warp switch W.

40 Grouped with terminal 24 are two terminals 25 and 26. Terminal 25 is connected by wire 27 with an electrical ignition system I which, in the drawing, is indicated as comprising a sparking mechanism 28 and an electro-magnetic pilot gas valve 29 which are connected by wire 30 with lead 10.

45 Terminal 26 is connected by wire 31 with a terminal 32 at one end of a mercury tube 33 which is supported upon a pivoted carrier 34. Wire 31 also leads to one end of the stator 35 of an induction motor VM which, through the medium of a reducing gear train 36 acts

upon a reciprocable plunger 37 which controls a fuel valve 38 in the fuel line leading to the burner. The opposite end of stator 35 is connected to a wire 39 which is connected to lead 10.

50 The valve motor VM is of a type which will permit stalling while under the influence of an energizing current and its action upon plunger 37 as opposed by a spring 40 which biases the plunger to valve closing position.

55 Associated with terminals 32 are two terminals 41 and 42. Terminal 41 is connected by wire 43 with wire 24' and consequently with blade 16 and terminals 23 and 24 of the combustion control C. Terminal 42 is connected by wire 44 with the main burner motor M, said motor also being connected with wire 39.

60 The motor M may drive an oil pump or moving parts of the burner.

65 Carrier 34 is connected at 50 with plunger 37 in such manner that, when the oil valve is closed, terminals 32, 41 and 42 will be electrically disconnected and when the oil valve is opened all of said terminals will be electrically connected.

70 The diagram shows the parts in cold position.

75 When heat is called for by thermostat T the circuit 11—T—12—13—14—19—18—16—24'—24—25—27—28—29—30—10 is established and the ignition mechanism I energized. At the same time the circuit 11—T—12—13—14—19—18—16—24'—24—26—31—35—39—10 is established, thus energizing the valve motor VM to raise plunger 37 against 80 the action of spring 40 and open valve 38.

85 The opening movement of plunger 37 shifts the interlock and main motor switch to establish a maintaining circuit for the valve motor and energizing circuit for the burner motor. 90 The maintaining circuit is 11—T—12—13—14—19—18—16—24'—43—41—32—31—35—39—10, thus making a valve motor circuit independent of the combustion control C. The main motor circuit is 11—T—12—13—14—19—18—16—24'—43—41—42—44—M—39—10.

95 If, for any reason, ignition of the fuel fails there will be no change of circuits at the combustion control C and, in a predetermined time, the flow of current through the heating coil 18 will warp blade 16 and cause a break of all circuits at 13—14.

If proper ignition occurs the combustion control C will shift to break connection between terminals 24, 25 and 26 and to make connection between terminals 21 and 23, thus shunting the heating coil 18 as follows: 11—
5 T—12—13—14—19—20—21—23—24—43—
32—31 to stator 35, and 42—44 to motor M.

If, for any reason, combustion fails after initial ignition the combustion control will 10 return to the cold position thereby breaking connection at 21—23 whereupon the ignition means is again energized to produce ignition, if possible. If such ignition occurs promptly the combustion control will be returned to its 15 hot position but if re-ignition does not occur promptly coil 18 will be heated to cause a break of all circuits at 13—14, whereupon manual re-set of the apparatus becomes necessary.

If, for any reason, the combustion control should be improperly placed or held in hot position, by shorting across 21—23 or otherwise, when the apparatus was cold, the whole apparatus will become inoperative and non- 20 responsive to thermostat T. If, on the other hand, such an improper manipulation of combustion control C should take place after it had been carried, by heat at the burner, to hot position, a break of the circuit at T will, 25 of course, de-energize the valve motor and fuel motor circuits, thus stopping the fuel motor and permitting the valve motor to be returned to normal, thus returning switch carrier 34 to normal whereupon, because of 30 the break between 32, 41 and 42, the apparatus will be out of commission until the combustion control C is restored to its normal condition.

While I have illustrated mercury tube 40 switches at various points it will be readily understood that any desired form of circuit-breaker suitable for handling the necessary current may be substituted without departing from my invention.

It will also be understood that the 45 details of motor VM and its connection with the switch actuated thereby may be considerably modified and that it is not absolutely essential that this motor actuates a fuel valve 50 because, while such a valve is quite desirable to insure against leakage of fuel past the fuel delivering apparatus driven or controlled by motor M, such apparatus controlled by motor M may be solely relied upon to control the 55 flow of fuel.

For convenience motor M may be called 60 the fuel motor and motor VM may be called the supplemental motor. The details of the warp switch may be varied, the essential 65 characteristics being that there be a retarded circuit-breaking action after a predetermined time interval of current flow in the absence of combustion at the burner, and the term warp switch in the claims is used to designate such 70 a device generally and the term heating coil

is used to designate generally the element thereof electrically causing delayed circuit-breaking action. The term room thermostat 75 is used to designate a main circuit controlling element sensitive to thermal or other conditions to be affected at a remote point by the burner.

I claim as my invention:

1. In a control system for fluid-fuel burners; a supplemental electric motor; an energizing circuit for said supplemental motor comprising a warp switch and its heating coil, and a circuit-breaker sensitive to combustion conditions adjacent the burner; a maintaining circuit for said supplemental motor comprising the warp switch, a circuit-breaker sensitive to combustion conditions adjacent the burner and capable of cutting out the heating coil, and a circuit-breaker actuated by the supplemental motor; a burner motor; an energizing circuit for said burner motor comprising the warp switch and its heating coil and a circuit-breaker actuated by the supplemental motor; and a maintaining circuit for the burner 90 motor comprising said last mentioned circuit-breaker and the circuit-breaker which cuts out the heating coil.

2. In a control system for fluid-fuel burners; a supplemental electric motor; an energizing circuit for said supplemental motor comprising a warp switch and its heating coil, and a circuit-breaker sensitive to combustion conditions adjacent the burner; a maintaining circuit for said supplemental motor comprising the warp switch, a circuit-breaker sensitive to combustion conditions adjacent the burner and capable of cutting out the heating coil, and a circuit-breaker actuated by the supplemental motor; a burner 95 motor; an energizing circuit for said burner motor comprising the warp switch and its heating coil and a circuit-breaker actuated by the supplemental motor; a maintaining circuit for the burner motor comprising said last mentioned circuit-breaker and the circuit-breaker which cuts out the heating coil; electric ignition means, and an energizing circuit therefor comprising the warp switch and a circuit-breaker sensitive to combustion 100 conditions adjacent the burner.

3. In a control system for fluid-fuel burners; a supplemental electric motor; a reciprocal element actuated in one direction by said motor; means biasing said reciprocal member against said motor; a fuel valve associated with said reciprocal member; an actuating circuit for said supplemental motor comprising a warp switch and its heating coil 110 and a circuit-breaker sensitive to combustion 115 conditions adjacent the burner; a maintaining circuit for said supplemental motor comprising the warp switch, a circuit-breaker sensitive to combustion conditions adjacent the burner and capable of cutting out the burner and capable of cutting out the 120

heating coil, and a circuit-breaker associated with said reciprocable member; a burner motor; an energizing circuit for said burner motor comprising the warp switch and its 5 heating coil and a circuit-breaker associated with said reciprocable member; a maintaining circuit for the burner motor comprising said last mentioned circuit-breaker and the circuit-breaker which cuts out the heating 10 coil; electric ignition means; and an energizing circuit therefor comprising the warp switch and a circuit-breaker sensitive to combustion conditions adjacent the burner.

4. In a control system for fluid-fuel burners; a supplemental electric motor; a reciprocable element actuated in one direction by said motor; means biasing said reciprocable member against said motor; an actuating circuit for said supplemental motor comprising a warp 20 switch and its heating coil and a circuit-breaker sensitive to combustion conditions adjacent the burner; a maintaining circuit for said supplemental motor comprising the warp switch, a circuit-breaker sensitive to combustion 25 conditions adjacent the burner and capable of cutting out the heating coil, and a circuit-breaker associated with said reciprocable member; a burner motor; an energizing circuit for said burner motor comprising the 30 warp switch and its heating coil and a circuit-breaker associated with said reciprocable member; and a maintaining circuit for the burner motor comprising said last mentioned circuit-breaker and the circuit-breaker which 35 cuts out the heating coil.

5. In a control system for fluid-fuel burners; a supplemental electric motor; a reciprocable element actuated in one direction by said motor; means biasing said reciprocable member against said motor; a fuel valve associated 40 with said reciprocable member; an actuating circuit for said supplemental motor comprising a warp switch and its heating coil and a circuit-breaker sensitive to combustion conditions adjacent the burner; a maintaining circuit for said supplemental motor comprising the warp switch, a circuit-breaker sensitive to combustion 45 conditions adjacent the burner and capable of cutting out the heating coil, and a circuit-breaker associated with said reciprocable member; a burner motor; an energizing circuit for said burner motor comprising the warp switch and its heating coil and a circuit-breaker associated with said reciprocable member; and a maintaining circuit for the burner motor comprising said last mentioned circuit-breaker and the circuit-breaker which 50 cuts out the heating coil.

6. In a control system for fluid-fuel burners; a supplemental electric motor; a reciprocable element actuated in one direction by said motor; means biasing said reciprocable member against said motor; an actuating circuit for said supplemental motor comprising a warp 55 switch and its heating coil and a circuit-

breaker sensitive to combustion conditions adjacent the burner; a maintaining circuit for said supplemental motor comprising the warp switch, a circuit-breaker sensitive to combustion conditions adjacent the burner and capable of cutting out the heating coil, and a circuit-breaker associated with said reciprocable member; a burner motor; an energizing circuit for said burner motor comprising the warp switch and its heating coil and a circuit-breaker associated with said reciprocable member; a maintaining circuit for the burner motor comprising said last mentioned circuit-breaker and the circuit-breaker which cuts out the heating coil; electric ignition means; and an energizing circuit therefor comprising the warp switch and a circuit-breaker sensitive to combustion conditions adjacent the burner.

7. In a control system for fluid-fuel burners; a supplemental electric motor; a reciprocable element actuated by said motor; a fuel motor; a warp switch comprising a heating coil; circuit-breaking means actuated by the supplemental motor comprising three associated terminals and means for simultaneously making or breaking circuits thereat; circuit-breaking means sensitive to combustion conditions adjacent the burner comprising a hot group of two terminals and a cold group of two terminals and means for alternately connecting the terminals of said groups; electric connections between the warp switch, the heating coil, one terminal of each group of the circuit-breaking means sensitive to combustion conditions, and one terminal of the motor-actuated circuit-breaker; electric connections between one terminal of the cold group of the circuit-breaker sensitive to combustion conditions and the warp switch, shunting the heating coil; electric connections between one terminal of the cold group of the circuit-breaker sensitive to combustion conditions, one terminal of the motor-actuated circuit-breaker and the supplemental motor; electric connections between the fuel motor and one terminal of the motor-actuated circuit-breaker; and power terminals for the fuel motor and warp switch.

8. In a control system for fluid-fuel burners; a supplemental electric motor; a reciprocable element actuated in one direction by said motor; means biasing said element against the motor; a fuel motor; a warp switch comprising a heating coil; circuit-breaking means actuated by the reciprocable element comprising three associated terminals and means for simultaneously making or breaking circuits thereat; circuit-breaking means sensitive to combustion conditions adjacent the burner comprising a hot group of two terminals and a cold group of two terminals and means for alternately connecting the terminals of said groups; electric connections between the warp switch, the heating coil, one terminal of each group of the circuit-breaking

- means sensitive to combustion conditions, and one terminal of the motor-actuated circuit-breaker; electric connections, between one terminal of the cold group of the circuit-breaker sensitive to combustion conditions and the warp switch, shunting the heating coil; electric connections between one terminal of the cold group of the circuit-breaker sensitive to combustion conditions, one terminal of the motor-actuated circuit-breaker and the supplemental motor; electric connections between the fuel motor and one terminal of the motor-actuated circuit-breaker; and power terminals for the fuel motor and warp switch.
9. In a control system for fluid-fuel burners; a supplemental electric motor; a reciprocable element actuated by said motor; a fuel motor; a warp switch comprising a heating coil; circuit-breaking means actuated by the supplemental motor comprising three associated terminals and means for simultaneously making or breaking circuits thereat; circuit-breaking means sensitive to combustion conditions adjacent the burner comprising a hot group of two terminals and a cold group of three terminals and means for alternately connecting the terminals of said groups; electric connections between the warp switch, the heating coil, one terminal of each group of the circuit-breaking means sensitive to combustion conditions, and one terminal of the motor-actuated circuit-breaker; electric connections, between one terminal of the cold group of the circuit-breaker sensitive to combustion conditions and the warp switch, shunting the heating coil; electric connections between one terminal of the cold group of the circuit-breaker sensitive to combustion conditions, one terminal of the motor-actuated circuit-breaker and the supplemental motor; electric connections between the fuel motor and one terminal of the motor-actuated circuit-breaker; electric ignition means; electric connections between one terminal of the cold group of the circuit-breaker sensitive to combustion conditions, the ignition means, and a power terminal; and power terminals for the fuel motor and warp switch.
10. In a control system for fluid-fuel burners; a supplemental electric motor; a reciprocable element actuated in one direction by said motor; means biasing said element against the motor; a fuel motor; a warp switch comprising a heating coil; circuit-breaking means actuated by the reciprocable element comprising three associated terminals and means for simultaneously making or breaking circuits thereat; circuit-breaking means sensitive to combustion conditions adjacent the burner comprising a hot group of two terminals and a cold group of three terminals and means for alternately connecting the terminals of said groups; electric connections between the warp switch, the heating coil, one terminal of each group of the circuit-breaking means sensitive to combustion conditions, and one terminal of the motor-actuated circuit-breaker; electric connections, between one terminal of the cold group of the circuit-breaker sensitive to combustion conditions, one terminal of the motor-actuated circuit-breaker and the supplemental motor; electric connections between the fuel motor and one terminal of the motor-actuated circuit-breaker; electric ignition means; electric connections between one terminal of the cold group of the circuit-breaker sensitive to combustion conditions, the ignition means, and a power terminal; and power terminals for the fuel motor and warp switch.

In witness whereof, I, Paul F. Shivers, have hereunto set my hand at Wabash, Indiana, this 30th day of April, A. D. one thousand nine hundred and twenty-seven.

PAUL F. SHIVERS.
